UNITED STATES PATENT OFFICE

WILLIAM E. BROCK, OF PLAINFIELD, NEW JERSEY.

MOLD FOR VENEERING LUMBER.

SPECIFICATION forming part of Letters Patent No. 445,605, dated February 3, 1891.

Application filed April 3, 1890. Serial No. 346,404. (No model.)

To all whom it may concern:

Be it known that I, WILLIAM E. BROCK, a citizen of the United States, and a resident of Plainfield, in the county of Somerset and 5 State of New Jersey, have invented certain new and useful Improvements in Molds for Veneering Lumber, of which the following is a specification.

My invention is a mold designed to be used 10 in the process of applying a veneer to either surface and the edges of planks or boards, its essential features being hereinafter fully described, and illustrated in the accompanying drawings, in which—

15 Figure 1 represents an end view of the mold closed and with a board in position therein. Fig. 2 represents a like view of the mold opened. Fig. 3 represents an end view of a modification in the shape thereof. Fig. 20 4 represents a plan or top view, partly in section, of a portion thereof.

Similar letters of reference indicate similar parts.

The letters A B indicate two sections into 25 which the mold is divided longitudinally with the sections alongside of each other, and C indicates one of a series of joints by which the sections are hinged together at the bottom of the mold for permitting them to swing 30 in vertical planes to and from each other. Each of the sections A B is constructed to conform in cross-section with one edge of the board D that is to be veneered, and in the example shown in Figs. 1 and 2 the sections 35 have respectively an angular projection e and angular cavity e', while in the example shown in Fig. 3 they have respectively a tongue f and groove f', these parts e e' or f f' being at the opposite sides of the mold and 40 joined by a flat intervening surface e² or f². One of the mold-sections—namely, A—is also formed with a shoulder s at the top of the projection e or tongue f to form an abutment for the veneer o, that may be introduced in 45 the mold, and to both ends of the section B is attached one end of a strip, as at G, which indicates the strip at one end of the mold, the other or free end of which strip projects from such section and enters a recess I of the 50 hinged section A, thus intersecting the line of division between the sections, said strip and recess forming jointly a stop for regulat-

ing the opened position of the sections by contact of the strip with the upper edge of the recess, as shown in Fig. 2. The projecting 55 end of the strip G has a less area of width than the recess I, thus permitting the required adjustment of the sections A B relatively to each other—namely, by a play of the strip in the recess—and in the example shown 60 in Figs. 1 and 2 the upper edge of the strip is inclined outward and downward, while in the example shown in Fig. 3 the upper edge of the recess is inclined inward and upward for graduating such less width of the strip, 65 or vice versa.

When the mold is applied to use, the sections A B are spread apart or opened as far as the stop G. I may allow, and a veneer cut to the proper size is laid in the mold with its 70 one edge abutting against the shoulders and its other edge against the base of the cavity e' or groove f', as shown by dotted lines in Fig. 2. The board properly glued is then adjusted between the mold-sections, and the 75 latter are returned to a normal or closed position, whereby the veneer is shaped to the board and firmly secured thereto. By regulating the opened position of the mold-sections they are adapted to receive and hold 80 the veneer in proper relation to the board subsequently introduced between them for bringing the veneer upon the desired portions of the board, especially when the veneer is laid in the mold, so as to abut against the shoulder s, as indicated in Fig. 2, while the adjustment of the sections, moreover, is thereby facilitated.

By the construction of the mold-sections with an angular fin or projection e and corresponding cavity e' they readily adapt themselves to any slight inequalities of dressing in the lumber and acquire a tendency to firmly interlock with the board when closed, so that no clamp is required to be used after the veneer has been shaped and while it is drying on the board. In practice the mold is laid on a bed which shall permit the joints C to sink therein, as shown in Fig. 1, bringing the mold in contact with the bed mainly at its outer 100 lower corners, and to insure the condition last named the bottom of both mold-sections may be inclined in an inward and upward direction, as shown in Fig. 1.

What I claim as new, and desire to secure by Letters Patent, is—

A lumber-veneering mold having two sections hinged together at the bottom of the 5 mold to swing in vertical planes, each constructed to conform with one edge of a board, and one constructed at its upper part with a shoulder forming an abutment for the veneer introduced in the mold, in combination with 10 a stop for regulating the opened position of the

mold-sections, consisting of an end recess in one section and a strip of the other section entering said recess, forming jointly a stop for regulating the opened position of the mold-sections, substantially as and for the purpose 15 described.

WILLIAM E. BROCK.
